UNITED STATES PATENT OFFICE.

CAREY A. CHESHIRE, OF DES MOINES, IOWA.

FEEDING MECHANISM.

1,073,215.

Specification of Letters Patent. Patented Sept. 16, 1913.

Application filed June 12, 1912. Serial No. 703,144.

To all whom it may concern:

Be it known that I, CAREY A. CHESHIRE, a citizen of the United States, and a resident of the city of Des Moines, county of Polk, 5 and State of Iowa, have invented certain new and useful Improvements in Feeding Mechanisms, of which the following is a specification.

This invention relates to new and useful 10 improvements in feeding mechanisms to be used in connection with printing presses, ruling machines, mailing machines, addressing machines, book gathering or collating machines, and like mechanisms; the same being a substitute for the application filed June 5th, 1911, Serial No. 631,358.

It is the object of the present invention to provide a feeding mechanism whereby the 15 number of sheets delivered to the machine to which the device is attached may be gaged and regulated and the device be adjusted to various thicknesses or sizes of articles to be delivered to the machine.

Among the other objects of the present invention, it is designed to provide a means whereby the article may be delivered to the feed rolls of the attached machine without any sagging thereof whatsoever, in order that the same may pass through said feed 20 rolls and be delivered to the attached machine in perfect condition.

With the above and other objects in view, this invention consists in the construction, combination and arrangement of parts, all as 25 hereinafter more fully described, claimed and illustrated in the accompanying drawings wherein:—

Figure 1 is a central longitudinal section of a device constructed in accordance with 30 the present invention, Fig. 2 is a top plan view thereof, and Fig. 3 is a partial section taken along line 3—3 of Fig. 1.

Reference being had more particularly to the drawings, 10 indicates generally a frame 45 provided with a central guide bar 11. A T-bar 12 is mounted for reciprocation in the guide bar 11 and carries the transversely arranged supporting bar 14^a which is disposed at right angles to the bar 12. Mounted 50 in the frame 10 adjacent to the bar 11 are the printing cylinders 13 or a mechanism to which the articles are being fed. Adjacent to the cylinders 13 and interposed between said cylinders and the bar 11 are the 55 feeding rollers 14 which are mounted upon the shafts 15 extending transversely in the

frame 10. It will be observed that said rollers 14 are arranged in coöperating pairs spaced apart so as to provide spaces between them. A plurality of bearings 16 are formed upon the sides of the frame 10 and for the rods 17 and 17^a interposed therebetween. These rods carry the longitudinal rods 18 which are interposed therebetween, said rods 18 having the vertical side bars 19 secured thereto. The rear rod 17^a carries the vertical rear rods 21 by means of the brackets 20. This mechanism heretofore described composed of the rods 17, 17^a, 18, 19 and 21, 60 comprises a hopper in which the sections of books, paper, cardboard, envelops, etc., are placed. A plate 22, which is illustrated curved in formation but which may be flat if desired, is mounted upon the transverse rod 14^a by means of the bearing 23, and is 65 adapted to reciprocate as the bar 12 reciprocates. The rear end of this plate 22 is provided with the slots 24 which are adapted to receive the vertical rods 21 carried by the rod 17^a in order that the plate may travel 70 rearwardly as far as possible in order that the hooks or sheet engaging members 25 may engage the rear edge of the bottom sheet or section of book. The bar 17 is provided with a bracket 26 in which a gate or 75 stop bar 27 is mounted for reciprocation, said stop bar or gate being retained in adjusted positions by the set screw 28. This bar 27 rests in a vertical plane substantially 80 tangential to the rollers 14. The plate 22 is provided with a central forwardly extending finger 29 which is equal in length to the distance between the outer face of the stop bar 27 and the inner vertical tangential points 85 of the shafts 15, in order that said finger 90 may readily conduct the paper to said rollers and insure the engagement thereof by the same, as will hereinafter be more fully described.

From the foregoing it will clearly be 100 seen that as the plate 22 reciprocates through the instrumentality of the bar 12, the stack of sections of books or sheets of paper 30 carried thereby will be engaged by the stop bar 27 and be retained in the hopper constituted by the vertical rods 19 and 21. The bottom sheet will therefore be carried forward by the plate 22, the finger 29 of said plate passing between the two central rollers 17 and extending therethrough 105 until the sheet of paper is engaged by the feed rollers 14. These rollers carry the 110

sheet of paper or section of book between the cylinders 13 and insure the positive delivery of said article to the cylinders in perfect condition and without sagging. By 5 providing a gate or stop bar 27 with an adjustment, it is possible to adapt the feeding mechanism to all thicknesses of articles, it being possible to vary the same according to the work. The finger 29 supports the 10 outer edge of the sheet to be delivered to the press and does not permit the same to sag prior to this engagement by the feeding rollers 14, the space between the finger 29 and the stop bar 27 being equal to the 15 article operated upon.

While I have illustrated and described the preferred form of construction for carrying my invention into effect, this is capable of variation and modification without 20 departing from the spirit of the invention. I, therefore, do not wish to be limited to the exact details of construction set forth, but desire to avail myself of such variations and modifications as come within the scope 25 of the appended claims.

Having described my invention what I claim as new and desire to secure by Letters Patent is:

1. The combination with a plurality of 30 coöperating pairs of feed rollers spaced apart, of a hopper; and a downwardly

curved reciprocatory base plate for said hopper adapted to remove articles therefrom, said base plate being provided at its forward end with a single centrally projecting finger arranged to pass into a space between said pairs of rollers and deliver articles thereto, said finger being downwardly curved to correspond to said base plate, substantially as described. 35

2. The combination with feed rollers of a hopper; a downwardly curved reciprocatory base plate for said hopper provided with a forwardly and centrally extending finger, said finger being downwardly curved 40 to correspond to said base plate; and a vertically adjustable stop bar positioned over said finger, substantially as described.

3. The combination with feed rollers, of a hopper; a downwardly curved reciprocatory base plate for said hopper provided 50 with a single forwardly and centrally extending finger; and a stop bar positioned over said finger, substantially as described.

In testimony whereof I have signed my 55 name to this specification in the presence of two subscribing witnesses.
